UNITED STATES PATENT OFFICE.

FRANK H. FRENCH, OF PRESTON, IOWA.

ADJUSTING MECHANISM FOR DISK HARROWS.

1,277,400.

Specification of Letters Patent.

Patented Sept. 3, 1918.

Application filed March 13, 1917, Serial No. 154,427. Renewed January 25, 1918. Serial No. 213,817.

To all whom it may concern:

Be it known that I, FRANK H. FRENCH, citizen of the United States of America, and resident of Preston, Jackson county, 5 Iowa, have invented a new and useful Adjusting Mechanism for Disk Harrows, of which the following is a specification.

The object of this invention is to provide an improved yielding pressure adjusting mechanism particularly adapted for 10 use in connection with the control of the elevation of inner ends of pivoted gangs of disk harrows.

A further object of this invention is to 15 provide improved mechanism for manually adjusting the elevation of inner ends of pivoted gangs of disk harrows and at the same time permitting independent vertical movement of the inner end of one of said 20 gangs without affecting the position or adjustment of the other of said gangs.

A further object of this invention is to 25 provide improved yielding pressure mechanism for permitting independent vertical movement of either gang of disks under unusual strain.

A further object of this invention is to 30 provide improved yielding pressure mechanism for permitting independent vertical movement of either gang of disks under unusual strain; together with manually controlled yielding pressure mechanism for simultaneously adjusting the altitude of the inner ends of both gangs.

35 My invention consists in the construction, arrangement and combination of elements hereinafter set forth, pointed out in my claims and illustrated by the accompanying drawing, in which—

40 Figure 1 is a side elevation showing my improved adjusting mechanism as applied to a disk harrow, a fragmentary portion only of which is shown. Fig. 2 is a rear elevation of the same, partly in section.

45 Fig. 3 is a bottom plan of the pivoted yoke and hanger bars.

In the construction of the mechanism as 50 shown the numerals 10, 11 designate the separate members of the pole bar of a disk harrow which are spaced apart and secured at their rear ends to the central portion of the frame (not shown) of the harrow and adapted to receive attachment at their forward ends of any suitable draft means. The 55 disk gangs (not shown) are mounted end

to end behind the pole bars 10, 11 and suitable means is provided for altering the inclination of said gangs simultaneously relative to the line of draft of the device; such means including set lever bars 12, 13 and 60 hand levers (not shown) for shifting said set lever bars longitudinally to adjust the position of the inner ends of the gangs, said set lever bars also being subject to manipulation, as hereinafter more fully explained, 65 to adjust the elevation of the inner ends of the gangs. My present invention relates to the latter named adjustment and is an improvement on the devices illustrated, described and claimed in my application for 70 Letters Patent of the United States filed November 27, 1916, Serial Number 133,519, to which application reference hereby is made.

A swinging yoke is provided and is 75 formed of arms 14, 15 mounted outside of and in sliding contact with the pole bars 10, 11, said arms being pivoted at their forward ends to said pole bars by a bolt or pin 16, transversely mounted. The arms 80 14, 15 extend rearwardly alongside the pole bars 10, 11 and are rigidly jointed at their rear ends by a cross-bar 17 extending across the tops of said pole bars and limiting downward movement of said arms on the 85 pivot 16. Spaced ears 18 are formed on and project upwardly from the central portion of the cross-bar 17, and an arcuate rod 19 is pivoted to and between said ears by a bolt or pin 20, said arcuate rod extending 90 forwardly and upwardly from said pivot. An adjusting lever 21 is fulcrumed at its lower end on the bolt or rod 16, and is provided with detent devices 22 for engaging a segment 23 carried by the pole bars, or one 95 of them, for holding said lever in any position in which it may be placed manually. The opposite end of the arcuate guide rod 19 is loosely and pivotally connected to an intermediate portion of the adjusting lever 100 21, preferably passing slidably through an eye 24 swiveled in the side of said lever, and having a stop member 25 on its end beyond said eye, such as a washer held in place by a key 26. An expansive spring 27 is coiled 105 on the arcuate guide rod 19 between the ears 18 and the eye 24 and forms a yielding connection between the lever and the swinging yoke. Rearward movement of the adjusting lever 21 compresses the spring 27 to a 110

certain extent and exerts a downward pressure on the swinging yoke, and forward movement of said lever relieves such pressure and exerts a pull on the arcuate guide 5 rod 19 through the eye 24 and washer 25, thus pulling upwardly on the rear or free end of the swinging yoke. A stud 28 is formed on and projects laterally from one or both of the pole bars 10, 11 and through 10 one or more curved slots 29 in the rear portion of the yoke arms, to form a sliding connection between the pole bars and rear portion of the yoke.

At their rear end portions the yoke arms 15, 16 are formed with integral downward extensions 14^a, 15^a, substantially at right angles to their main portions. The extensions 14^a, 15^a are connected by spaced cross-bars 30, 31 beneath the pole bars 10, 11 and 20 limiting upward movement of the rear end of the swinging yoke. Hanger arms 32, 33 are pivoted to opposite sides of the lower rear portion of the swinging yoke, are curved or offset downwardly intermediate 25 of their ends, each of said hanger arms extending inwardly from its pivot and across the median line of the device and beyond the outer margins of the swinging yoke. The hanger arms 32, 33 are formed with holes 34, 35 respectively in their outer end portions, which holes loosely embrace intermediate portions of the set lever bars 12, 13 respectively. The hanger arms 32, 33 are mounted between and each adjacent to one 30 of the cross-bars 30, 31, and lugs 36, 37 are formed on the downward extensions 14^a, 15^a and project downwardly between said hanger arms. Bolts 38, 39, preferably having countersunk heads, are mounted between 35 the members 31—36 and 32—37 respectively and form the pivots for the hanger arms 32, 33, thus providing a double bearing for each of said pivots as well as guides for oscillation of said hanger arms, said cross-bars and lugs preferably extending downwardly a material distance from the bottoms 40 of the extensions 14^a and 15^a.

Lugs 40, 41 are formed on and project 45 outwardly from rear end portions of the yoke arms 14, 15 respectively, and bolts 42, 43 are pivotally connected to outer end portions of the hanger arms 32, 33 respectively and pass upwardly and loosely through said lugs. Each bolt 42, 43 is formed with an 50 eye on its lower end pivoted to and between upstanding ears 47 on the hanger arms, by means of bolts 48. The bolts 42, 43 preferably are threaded throughout major portions of their lengths, and nuts 49 are 55 screwed thereon and located adjacent the lower ends, near the hanger arms 32, 33. Coil springs 44, 45 are mounted on the bolts 42, 43 respectively, between the nuts 49 and lugs 40 and 41, and nuts 46 are screwed on 60 the ends of said bolts above said lugs to 65 provide a connection between the parts and also as a means for alining the inner ends of the gangs. The nuts 49 serve as stops for the springs 44, 45 and also as a means for adjusting the tension of said springs by 70 adjusting of said nuts on the bolts.

In practical use the lever 21 is manipulated to adjust the vertical position of the rear end of the swinging yoke relative to the pole bars 10, 11, as limited by the upper 75 cross-bar 17 and lower cross-bars 30, 31. This causes a vertical adjustment of the hanger arms 32, 33 bodily and consequently of the set lever bars 12, 13 engaged by them, to the end of vertically adjusting the inner 80 ends of the disk gangs as desired, as to accommodate the horizontal inclination of the gangs to the surface over which the machine is traveling. At any position of adjustment of the swinging yoke and members 85 carried and engaged thereby, either of the hanger arms 32, 33 may rise independently of the other against the tension of the springs 44, 45, thus permitting an independent vertical movement of the gang 90 controlled thereby as when striking an obstruction such as a stone, and without in any manner affecting the vertical position of the other gang as controlled through the lever. Such independent movement of either disk 95 gang is occasioned by an upward movement of the corresponding set lever bar 12 or 13 pushing upwardly on the corresponding hanger arm 32 or 33 and causing an oscillation of said hanger arm on its pivot, 100 thereby compressing the corresponding spring 44 or 45 against the lug 40 or 41; and when such pressure is relieved the spring forces the hanger arm and with it the set lever bar back to its normal position of adjustment.

I claim as my invention—

1. A mechanism of the class described, comprising a yoke pivoted at one end, means for manually adjusting the opposite 110 end of said yoke, independent hanger arms pivoted on said yoke and formed with means for engaging members to be adjusted, and yielding pressure devices interposed between said hanger arms and the yoke.

2. A mechanism of the class described, comprising a yoke pivoted at one end, means for manually adjusting the opposite end of said yoke, means for limiting oscillatory movement of said yoke, independent hanger arms pivoted at one end of said yoke, said hanger arms being formed with means for engaging devices to be adjusted, and yielding pressure devices regulating vertical 120 movement of the free end of said hanger 125 arms.

3. A mechanism of the class described, comprising a yoke pivoted at one end, means for manually adjusting the opposite end of said yoke, including a yielding pres- 130

sure device between said adjusting means and the yoke, independent hanger bars pivoted at one end on said yoke and formed with means for engaging members to be adjusted, and yielding pressure devices regulating oscillatory movement of the free ends of said hangers.

4. A mechanism of the class described, comprising a yoke pivoted at one end, 10 means for manually adjusting the opposite end of said yoke, hanger bars pivoted at one end to said yoke and extending in opposite directions across the median line thereof, said hanger bars being formed at their free 15 ends with means for engaging devices to be adjusted, and yielding pressure devices engaging the free ends of said hanger arms.

5. A mechanism of the class described, comprising a member pivoted at one end, 20 means for manually adjusting the opposite end of said member, hanger bars pivoted at one end to said pivoted member and formed at their opposite ends with means for engaging devices to be adjusted, and adjustable yielding pressure devices engaging the 25 free ends of said hanger arms.

6. A mechanism of the class described, comprising, in combination with members adapted for vertical adjustment, a member 30 pivoted at one end, means for vertically adjusting the free ends of said pivoted member, hanger arms pivoted at one end to said pivoted member and formed at their free ends with means engaging said members, yielding pressure devices engaging the free 35 ends of said hanger arms, and means for adjusting the tension of said pressure devices.

7. An adjusting mechanism, comprising, 40 in combination with spaced members adapted for vertical adjustment, a member pivoted at one end, means for vertically adjusting the free end of said member, hanger arms pivoted on opposite sides of and crossing beneath said pivoted member, said hanger arms embracing at their free ends said adjustable members, and yielding pressure devices engaging the free ends of said hanger arms.

50 8. An adjusting mechanism, comprising, in combination with a fixed member and a pair of spaced vertically adjustable members therebeneath, a yoke pivoted at its forward end on said fixed member, means on 55 said yoke adapted to engage said fixed member and limit oscillation of said yoke, hanger arms pivoted at one end to opposite sides of said yoke and embracing at their free ends said spaced adjustable members, 60 lugs projecting laterally from upper rear portions of said yoke, and springs between said lugs and free ends of the hanger arms.

9. In a disk harrow having pole bars and 65 set lever bars for controlling adjustment of separate disk gangs, a yoke pivoted to said

pole bars, means for adjusting said pivoted yoke, and separate members pivoted on said yoke, crossing the vertical plane of said pole bars, engaging and permitting independent vertical movement of said set lever bars.

70

10. In a disk harrow having pole bars and set lever bars for controlling adjustment of separate disk gangs, a yoke pivoted to said pole bars, means for adjusting said pivoted yoke, and separate spring-pressed members pivoted on said yoke and permitting independent vertical movement of the respective set lever bars independently of the adjustment of said yoke.

75

11. In a disk harrow having a frame member and spaced set lever bars therebeneath for controlling adjustment of separate disk gangs, a swinging member carried by said frame member, a spring pressure device adjustable to control the position of 80 said swinging member, and separate spring-pressed members pivoted on the lower side of said swinging member and embracing said set lever bars, whereby independent vertical movement of said set lever bars is 85 permitted irrespective of the adjustment of said swinging member.

90

12. In a disk harrow having a frame member and spaced set lever bars therebeneath for controlling adjustment of separate disk gangs, a swinging member carried by said frame member, yielding means for 95 manually adjusting the said swinging member, hanger arms separately pivoted on the lower side of said swinging member and 100 loosely engaging the respective set lever bars at their free ends, and adjustable yielding pressure connections between free ends of said hanger arms and said swinging member.

100

13. In a disk harrow having longitudinally arranged set lever bars for controlling separate disk gangs, hanger arms each pivoted at one end and at their opposite ends embracing said set lever bars, bolts pivoted 110 to the free end portions of said hanger arms, and adjustable suspending means for said bolts, whereby said set lever bars and the inner ends of the disk gangs may be brought into horizontal alinement.

105

14. In a disk harrow having set lever bars for controlling separate disk gangs, a frame member above said set lever bars, a member swingingly mounted on said frame member, separate hanger arms pivoted at one end to 120 said swinging member and each engaging at its opposite end a set lever bar, and adjustable means for suspending the free ends of said hanger arms from said swinging member, whereby the disk gangs may be 125 brought into horizontal alinement.

115

15. In a disk harrow having set lever bars for controlling separate disk gangs and a frame member above said set lever bars, a member swingingly carried by said frame 130

member, separate hanger arms pivoted at one end to said swinging member and projecting at their free ends beyond the margin thereof, free end portions of said hanger arms embracing the respective set lever bars, bolts pivoted to free ends of said hanger arms, said swinging member being formed

with apertured lugs above said hanger arms, coil springs on said bolts, and nuts screwed on the ends of said bolts above said lugs. 10

Signed by me at Des Moines, Iowa, this sixth day of March, 1917.

FRANK H. FRENCH.
